Eyra Ripley, & N. S. Vedder, of Troy, N.Y.

Assignor to

Johnson, Cox, & Bailey, & Co. of New York, N.Y.

Letters Patent, No. 741. - dated Oct. 30th 1855.

The schedule referred to in the Letters Patent, & making part of the same.

To all whom it may concern,

Be it known that we, Eyra Ripley, & N. S. Vedder, of Troy, in the County of Rensselaer, & State of New York, have invented or produced a new and original design for a Cook-stove, which we call the "Empire-City," and we do hereby declare, that the following is a full & exact description of the same, reference being had to the annexed isometrical drawing, making a part of this specification.

Our ornamental design for cook-stoves consists of the following combination & disposition of - The compound moulding a, (see y, z) around the edge of the top plate: the compound moulding b, (see w, x) as the border of the bottom plate: the compound moulding c, (see section at v, & at v') on the outer edge of the hearth plate: the stone work d, d, d, d, d, on the perpendicular corners of the stove: the cavetto or hollow mould-

ing e. combined with the bead moulding f, around the border of the large door A. & the small one B. of the oven, the fire door C. & the doors D. & E. of the upper front plate: the scolloped concave moulding g. arranged as the inner frame of the panel of each of the above enumerated doors, & as a border to each of the panels F. G. H. I. & as a cornice or cap to each leg j. & the several variously shaped swelling ornaments (h. h'. h". h'. h". h'. h"), with check-work bands, as center pieces of the panels of the several doors A. B. C. D. E. & of the panels F. G. H. I. in the inner corners of the north plate, & in the side faces of the ornamental shaped legs.

Having thus described our design, We claim the combination & arrangement of the several ornaments & mouldings, as herein described & represented in the annexed drawing, the whole forming an ornamental design for a cork-stove
